UNITED STATES PATENT OFFICE.

PHARES E. GETZ, OF NEOSHO, MISSOURI.

DESIGN FOR A MINNOW-TRAP.

46,993.

Specification for Design.

Patented Feb. 23, 1915.

Application filed October 13, 1914. Serial No. 866,555. Term of patent 7 years.

To all whom it may concern:

Be it known that I, PHARES E. GETZ, a citizen of the United States, residing at Neosho, in the county of Newton and State of Missouri, have invented a new, original, and ornamental Design for Minnow-Traps, of which the following is a specification, reference being had to the accompanying drawing, forming part thereof.

The figure is a perspective view of a minnow trap, showing my new design.

I claim:

The ornamental design for a minnow trap, as shown.

PHARES E. GETZ.

Witnesses:

FRED G. HUBBERT,
H. E. ARCULARIUS.
